UNITED STATES PATENT OFFICE.

EDGAR JEROME HOFFMAN, OF CHEROKEE, IOWA.

HANGER SUPPORT.

Application filed May 20, 1921. Serial No. 471,218.

To all whom it may concern:

Be it known that I, EDGAR J. HOFFMAN, a citizen of the United States, residing at Cherokee, in the county of Cherokee and 5 State of Iowa, have invented a new and useful Hanger Support, of which the following is a specification.

This invention relates to a tool especially designed for supporting cable hangers, while 10 the same are being applied to I beams or the like.

The primary object of the invention is to provide a tool of this character which will grip the upper portion of a flange of 15 an I beam, while the ends of the hanger are being bent therearound.

A further object of the invention is the provision of a tool of this character which may be adjusted to permit the use of the 20 device in connection with I beams having flanges of various thicknesses.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed, without departing from the spirit of the invention.

Referring to the drawing:—

Figure 1 is a side elevational view of a 30 tool constructed in accordance with the present invention, and showing the same as applied to an I beam.

Figure 2 is a front elevational view of the tool.

Referring to the drawing in detail, the device includes a pair of spaced curved arms 5 which have their lower extremities connected by means of the transverse bar 6, which is secured to the curved arms as by 40 means of the bolts 7 which pass through threaded openings in the arms and bar.

Formed in the arms 5 adjacent to the upper free ends thereof are suitable openings to accommodate the set screws 8 which are 45 adjustable through the arms to adapt the tool for use with I beams having flanges of various thicknesses.

Having connection with the arms 5 are the

movable jaws 9 which have their upper ends serrated as at 10 to bite into the hanger 55 to be positioned, to force the same into engagement with the I-beam to which the hanger is to be applied. A bolt indicated at 10' passes through suitable openings in the jaws and arms to pivotally connect the 60 jaws to the arms, there being provided a handle 11 formed integral with the jaws for operating the jaws to move the same to positions as illustrated by Figure 1 of the drawing, where the jaws are disclosed as 65 forcing the hanger which in the present drawing is indicated at 12, into engagement with the lower edge of the I beam.

In the use of the device, a hanger to be applied is positioned on the jaws 9, the 70 arms 5 being moved over the upper portion of the lower flange of an I-beam to which the hanger is to be applied, and the handle 11 is operated to force the hanger into engagement with the I-beam. It will be seen 75 that with the hanger supported in this position the ends of the hanger may be readily and easily bent over the lower flange of the beam to secure the hanger thereto.

A hook member 13 is formed at one end 80 of the handle 11, the hook member being especially designed for prying the hook from the beam, should it be found necessary to remove the same.

It might be further stated that while I 85 have shown and described adjusting screws for adapting the device for use in connection with I beams of various thicknesses, it is to be understood that the adjustment may be accomplished by providing an adjustable 90 handle 11.

What is claimed as new is:—

1. A tool of the class described comprising curved arms, jaws having pivotal connection with the arms, a handle having connection 95 with the jaws, and adjusting means disposed adjacent to the free ends of the arms.

2. A tool of the class described comprising curved arms, a bar for connecting the arms, jaws positioned between the arms and having serrated surfaces extending above the upper edges of the arms adjacent to the jaws, a handle for operating the jaws, and adjusting means positioned adjacent to the free ends of the arms.

3. In a tool of the class described, curved

arms, means for connecting the curved arms, an adjustable operating handle having connection with the curved arms, and adjusting means carried by the arms and adapted to contact with a beam for securing the tool to a beam.

5 In testimony that I claim the foregoing

as my own, I have hereto affixed my signature in the presence of two witnesses.

EDGAR JEROME HOFFMAN.
